COMBINATION SAFETY RAZOR AND COMB

Allen J. Parker, West Palm Beach, Fla.

Application January 18, 1956, Serial No. 39,831

Term of patent 14 years

(Cl. D86—8)

Fig. 1.

Fig. 2.

Fig. 3.

Fig. 4.

Figure 1 is a side elevation of a combination safety razor and comb, showing my new design,

Figure 2 is an edge view thereof,

Figure 3 is a longitudinal section taken substantially on line 3—3 of Figure 1 with portions of the handle shown in broken lines for the purpose of illustration and,

Figure 4 is an end view thereof.

I claim:

The ornamental design for a combination safety razor and comb, as shown and described.
